United States Patent Office

Des. 175,976
Patented Nov. 1, 1955

175,976

TEXTILE FABRIC

Patricia Ann Prichard, New York, N. Y., assignor to E-Z Mills, Incorporated, New York, N. Y., a corporation of New York

Application November 8, 1954, Serial No. 33,027

Term of patent 3½ years

(Cl. D92—1)

The figure is a view of the textile fabric, showing my new design.

I claim:

The ornamental design for a textile fabric, substantially as shown.
